UNITED STATES PATENT OFFICE.

HUGH B. COYLE AND FRANCIS X. COYLE, OF PHILADELPHIA, PENNSYLVANIA.

AWNIN.

SPECIFICATION forming part of Letters Patent No. 394,341, dated December 11, 1888.

Application filed October 24, 1888. Serial No. 289,031. (No model.)

To all whom it may concern:

Be it known that we, HUGH B. COYLE and FRANCIS X. COYLE, citizens of the United States, residing at Philadelphia, in the county 5 of Philadelphia and State of Pennsylvania, have invented certain new and useful Improvements in Awnings; and we do hereby declare that the following is a full, clear, and exact description of the invention, wherein—
10 Figure 1 is a side elevation of roll-support, with roll in section. Fig. 2 is a plan of same. Fig. 3 is a vertical longitudinal section of bearing-roller; Fig. 4, a plan, partly broken away, of swiveled arm; Fig. 5, a plan, partly broken away, of modification; Fig. 6, a perspective of awning, showing support in position. Fig. 7 is a vertical longitudinal section of roll, showing fastenings for canvas; and Fig. 8, a perspective of portion of awning 20 with hook and eye thereon.

Our invention has relation to awnings for use where occasion requires the rolling up and unrolling of the same.

Our invention has for its object the provision of novel means whereby the rolls of awnings of the above-mentioned class may be supported between their ends, and thereby relieved from any strain which might be imposed upon the same due to sagging.

30 A further object of our invention is the provision of a construction which will permit of the ready placing and removal of the awning-roll from its support without detaching or removing any of the parts of such support 35 and the perfect security of the awning-roll from being displaced when in position for use, such support not interfering in any way with the working of the awning and being cheaply manufactured and easily and 40 quickly applied.

A still further object of our invention is the provision of means for the efficient and perfect attachment and detachment of the awning from the roll, thereby obviating the 45 necessity of there being formed a hem or pocket on the edge of the awning and then forcing the roll through the opening formed by this hem, which has been the source of great annoyance and considerable labor.

50 A still further object of our invention is the provision of means whereby the side curtains

of rolling awnings may be easily and quickly folded into place preparatory to rolling up such awnings.

Our improvements consist in certain details of construction and in the combination of parts, as hereinafter fully described and claimed.

A represents the back or base plate of the device, which supports the roll B' of the awning C'. This awning may be operated through the medium of a chain or other convenient means for transmitting motion from a crank and pulley or wheel in a box. Such box is of the same construction as that shown in Letters Patent No. 294,767, granted H. B. Coyle, March 11, 1884. This support may be bolted or otherwise secured to the front of the building, having cast integral therewith, and extending for some distance from the bottom of plate A, a box-like section which is curved on both sides a', to correspond with the positions of the centers of the supporting-rollers B, C, and D, roller D being supported on extensions or arms d of such sides. It 70 will also be observed by reference to the drawings that arms d and sides a' are braced by the cross-piece or front a² of the box, which is also cast integral with the rest of the box.

Cast or formed on plate A, near the top and on the front of the same, is a square plate, E, having lugs e e' thereon, lugs e supporting the inner end of an arm, E', which carries the upper roller, F, for the awning to roll against in unwinding. This arm E', which has a downward curve or drop therein, so as to bring roller F close enough to roller D to prevent the passage of the roll B', is U-shaped at its inner end, arms e² e³ of this U-shaped or forked portion being tenoned, as shown at e⁴, and 85 fitting between lugs e e'. As will be observed, the upper arm, e², is swiveled by means of screw e⁵, which screw passes through lugs e and tenon e⁴, such screw being threaded into the lug opposite the side at which it enters. 90 This permits of the ready swinging of arm E' into or out of the way when desired without the unscrewing or removal of bolts when necessary to place the awning-roll therein or remove the same, as is the case where the support is made in separable sections, and serves 100 to keep all the parts in unyielding operative

relation at all times, and permits of the insertion and withdrawal of the awning-roll in a very short space of time and without the use of tools of any character.

5 In place of the old method of securing the awning to the roll, which is a very laborious matter, we provide pins g of large diameter, which pass through holes in the roll, which roll is hollow, and are formed with shoulders g' at their inner ends, which rest on the inner side of the roll B' . These pins have smaller portions, g^2 , formed thereon, which pass through corresponding openings in the side of the pipe or roll opposite that at which they enter, and are there riveted, as shown at g^3 . These shoulders and rivets keep said pins from being displaced. In the outer ends of these pins are holes or small openings g^4 , which holes are a sufficient distance from the roll to permit of the placing on the pins of the awning C , which awning has openings therein for the passage of pins g , said openings being surrounded with "grommets" or brass rings to keep the same from tearing. Through holes g^4 are passed spring-pins or "cotters" g^5 , for keeping the awning in place on pins g , and affording an easy and simple means of attaching and detaching the awning from roll B' , which is a great advantage where awnings 30 are of great length.

When the awning-roll B is in place and arm E' has been swung into position, a spring-pin or cotter or other convenient device, g^6 , is inserted through holes provided for its reception in lugs e' and lower tenoned arm, e^3 , thus securing said arm e^3 in its place, and preventing the upward movement of arm E' until pin g^6 is withdrawn.

As will be observed, pin g^6 is attached to a 40 chain, g^7 , which chain is in turn secured to staple g^8 in plate A , as will be readily appreciated. Chain g^7 prevents pin g^6 from becoming lost or misplaced when removed from its place in the lugs and keeps the same from 45 getting out of position when needed for use.

As shown in Fig. 1, awning-roll B' has a considerable quantity of canvas thereon, which causes the same to rest on all three of the rollers B , C , and D , roller F affording a 50 bearing for the canvas, and arm E' serving to keep the roll B' from jumping up. When a less quantity of canvas is on the roll B' , the same will rest on but two of the rollers, B and C .

55 By reference to Fig. 3 of the drawings it will be seen in what manner the bearing-rollers are supported. These rollers are made of hard wood, instead of rubber, as is generally employed, and has a longitudinal hole 60 bored in its center, in which is secured a brass pipe, d' , which serves the purpose of a journal-box for the bolt d^2 , on which said roller D is journaled. This bolt d^2 is threaded on its outer end and screws into one of the 65 sides a' , keeping said bolt in place, the other end being provided with the ordinary head formed thereon.

We prefer making the rollers of hard wood, as the canvas will slip easily over the same, while where rubber rollers are used the canvas 70 will bind or drag on such roller, by reason of the roughness of the canvas being opposed to the softness of the rubber, thus necessitating the exertion of more power in unrolling the awning than is requisite where wooden rollers 75 are employed.

In the aforementioned Letters Patent there is shown and described means for securing the side wings of the awning to the body thereof when the awning is to be rolled up. 80 This consists in the employment of an ordinary hook on the apex of the wing or curtain, which hook engages with an eye in the center of the awning, and, when the awning, with a "snap-hook" on the front of the building. 85 With this arrangement trouble has been experienced in engaging the hooks on the apices of the curtains with the eye in the center of the awning. This trouble we overcome by the employment of a ring, H , provided with a 90 loop, h , for sewing to the curtain, and a tapering shank, h' , between the loop and ring for grasping with a fork, h^2 , in the end of a pole. The object in tapering shank h' , it being thickest where it joins the ring, is to facilitate 95 the retaining of the shank in the fork when it is desired to hook the wing to the awning. If the shank were made straight instead of tapered, the curtain or wing of the awning would be blown by the wind out of the control of the 100 operator. With the shank made in this way, any strain due to the blowing of the wind or other cause will serve to wedge the shank more firmly in the fork. Owing to the shank being thin at its other end, a simple movement 105 of the fork in the direction of the thin portion will disengage the same.

When curtains are to be folded up preparatory to rolling up the awning, the ring on the apex of the curtain is carried by the pole 110 and fork to a hook on the inside of the awning, where ring H can be readily engaged with the hook I , as above explained. When the curtains are down, the ring H engages with a snap-hook, I' , on the front of the building, as 115 in the above-mentioned patent.

In some cases it may be found desirable to substitute in place of swiveled arm E' a jaw of the same width as the lower frame of the support for the awning-roll, in which case 120 there will be provided a pair of hinged tenons and a pair of pins for retaining the lower tenoned arms; or a single pin may be employed therein. This modification we have shown in Fig. 5 of the drawings, in which H is the upper jaw, and h k the hinged tenons on bolts k' , said tenons fitting between lugs l l' .

Having thus fully described our invention, what we claim as our invention is—

1. In an awning, a support for the roll 130 thereof, consisting of a rigid frame, in which are journaled the supporting-rollers, in combination with a normally-rigid hinged or swiveled arm for preventing the dislodgment

of said awning-roll from said support, substantially as shown and described.

2. In an awning, a support for the roll thereof, consisting of a swiveled or hinged arm for preventing the dislodgment of said roll from said support, and which is secured in unyielding engagement with a rigid frame, in which are journaled the supporting-rollers by a key or other device, substantially as shown and described.

3. In an awning, a support for the roll thereof, consisting in the combination, with the base-plate of such support, of a pair of swiveled arms or jaws, one above and opposed to the other, and supporting-rollers, each of said arms or jaws being held in unyielding operative positions by keys or other devices, as and for the purpose described.

4. In an awning, a support for the roll thereof, consisting in the combination of base-plate A, having integral therewith sections a' , terminating in arms d , and between which are secured the supporting-rollers B C D, said rollers being provided with pipes d' through their centers and journaled on bolts d^2 , said bolts being secured in sections a' , awning-roll B', awning C, arm E', and roller F, as and for the purpose set forth.

5. In an awning, C, and support for the roll B' thereof, the combination of base-plate A, having cast integral therewith sections a' , terminating in arms d , and in which are journaled the supporting-rollers B C D, arm E', carrying roller F, and being pivoted or hinged to lugs e on said base-plate by means of screw e^5 , passing through holes in said lugs and in arm e^2 of arm E', said arm E' swinging on screw e^5 , and being held rigidly in its normal position through the medium of a pin, g^6 , attached to chain g^7 , and passing through holes in lugs e' on the base-plate and arm e^3 , as and for the purpose set forth.

6. In an awning, the combination, with the

roll B', supported between its ends on rollers B C D, journaled in sections a' of the base-plate A, of diametrical pins passing through holes in the said awning and holes in said roll, to which roll they are riveted, on which pins the awning is fastened and prevented from becoming loose thereon by spring-pins 50 passing through holes in the heads of said diametrical pins, substantially as shown and described.

7. In an awning, the combination, with the roll B', supported between its ends on rollers B C D, journaled in sections a' of base-plate A, of pins g , passing through holes in said roll and awning and having shoulders g' , which abut against the inner side of the roll, and reduced portions g^2 , which pass through the 60 holes in the awning-roll and are formed at their outer ends into rivets g^3 , for securing pins g in place, spring-pins or cotters g^5 , passing through holes g^4 in the heads of said pins and keeping the awning in place on the pins, substantially as shown and described.

8. In an awning secured to roll B', said roll being supported between its ends on rollers B C D, journaled in sections a' of base-plate A, the combination, with the wings of such awning, of loops h , secured to said wings and having depending therefrom tapered shanks h' , terminating in rings H, for securing the wings to a hook in the building-front, said shank h' being grasped by a fork, h^2 , in the 75 end of a pole when necessary to engage ring H with hook I in the awning, as and for the purpose set forth.

In testimony that we claim the foregoing we have hereunto set our hands this 18th day 80 of October, A. D. 1888.

HUGH B. COYLE.
FRANCIS X. COYLE.
